UNITED STATES PATENT OFFICE

2,213,497

AIRPLANE PROPELLER

William H. Kelly, Denver, Colo.

Application June 21, 1938, Serial No. 214,887
Renewed December 22, 1939

5 Claims. (Cl. 170—159)

This invention relates to an improvement in propellers or impellers more particularly for use on air craft for either horizontal or vertical flight.

- 5 The principal object of this invention is to provide a propeller construction which will be more efficient than present type propellers and which will avoid the losses occasioned by radial slippage of the air stream.
- 10 The improved propeller is designed to project all of the air in the direction desired for propulsion and prevent the air from being thrown centrifugally outward.

The basic idea is to design a propeller which 15 will have circumferentially extending channels with side walls sufficiently deep to prevent the air from escaping radially or centrifugally from the blades so that all of the air will be projected rearwardly in a solid, powerful, propelling stream.

20 Other objects and advantages reside in the detail construction of the invention, which is designed for simplicity, economy, and efficiency. These will become more apparent from the following description.

25 In the following detailed description of the invention reference is had to the accompanying drawings which form a part hereof. Like numerals refer to like parts in all views of the drawings and throughout the description.

30 In the drawings:

Fig. 1 illustrates one embodiment of the invention.

Fig. 2 is a section therethrough taken on the line 2—2, Fig. 1.

35 Fig. 3 is a similar section illustrating the same construction with a greater pitch.

Fig. 4 is a similar section illustrating a still greater pitch.

Fig. 5 is an alternate form of the construction 40 of Fig. 1, in which the propelling cups are circumferentially curved.

Fig. 6 is a plan view of the form of Fig. 5.

Figs. 7, 8, and 9 illustrate various adaptations 45 of the principle of the invention.

45 Fig. 10 is a face view of a propeller in which the preferred form of the invention is embodied.

Fig. 11 is a rear view of the propeller of Fig. 10.

50 Figs. 12, 13, 14, 15, and 16 are blade sections of the form of Fig. 10, taken on the lines corresponding to their respective figure numbers.

The highly efficient effects of this propeller are obtained from the use of curved air-cups 55 mounted to rotate about an axis and opening in

the direction of rotary travel and at their rearward faces. In Fig. 1, two such cups are illustrated at 17 mounted on the extremities of radial arms 18 projecting from a hub 19. The cups 17 are scoop-shaped and completely curve-linear, as shown in Fig. 2 so that a line drawn on their surfaces at any point will be a curved line. The arms 18 pass completely through the cups to form a substantial, balanced support therefor. This relieves the cups of structural stress and allows them to be formed of relatively thin, light, material. All of the stresses are absorbed by the arms 18.

A streamlined shell or vane 20 surrounds the arm 18 where it crosses the cup to prevent the 15 arm from creating air resistance within the cup. The streamlined shell 20 is loosely mounted on the arm so that it may rotate to a position in the plane of least resistance in the air stream and, because of its shape, it presents very little 20 if any resistance to the flow of the air. When the propeller is not rotating, the vanes 20 hang vertically downward but when the propeller is rotated, the vanes 20 immediately assume their 25 most efficient position.

The curvature of the cups 17 may be designed 25 to produce any desired pitch, as shown in Figs. 2, 3, and 4 by the broken arrows.

Fig. 5 illustrates the same principle in another form. In this form, however, the inner faces 30 of the cups are flattened, as shown at 21, and curved upon a circumference around the hub so as to reduce any turbulence caused by the trailing edges thereof.

Figs. 7, 8, and 9 show quarter-spherical cups 35 mounted in various positions relative to the hub. The cups of Figs. 7 and 8 are inclined to offset the centrifugal or outward effect of the air and are designed to throw it in a compact rearward air stream. Fig. 9 illustrates the same principle 40 with the cups mounted at the hub without supporting arms.

In Fig. 10, the cups or pockets are embodied 45 in a radially extending propeller blade. The blades each consist of a curved outer shell 22 which is divided throughout its length by means of lateral partition plates 23; closed at its outer extremity by means of an end plate 24; and at its inner extremity by an inner end plate 25. The blades are supported upon tapered, tubular 50 arms 26 which extend radially outward from a hub member 27 throughout the entire length of the blade. The arms extend through, and are secured to, each of the partition plates 23. The plates 23 separate the blade length into curved 55

pockets having cross sections of the forms indicated in Figs. 12 to 16.

In each pocket, a stream-lined shell or vane 28 is mounted on the arm 26 and is free to rotate 5 thereon so as to automatically resume the most effective position for streamlining the arms 26.

While specific forms of the improvement have been described and illustrated herein, it is desired to be understood that the same may be 10 varied, within the scope of the appended claims, without departing from the spirit of the invention.

Having thus described the invention, what is claimed and desired secured by Letters Patent 15 is:

1. A propeller construction comprising: a hub; arms extending radially outward from said hub; scoop-shaped cups mounted on said arms, said cups being open in the direction of rotation and 20 at their rearward faces so as to receive a stream of air, curve it, and expel it rearwardly, said arms extending across said cups to support the latter; and stream-lined vanes formed on said arms within said cups.

25 2. A blade construction for propellers comprising: a hub member; a blade arm extending radially outward from said hub member; a curved propeller shell positioned to receive a stream of air from the direction of rotation and discharge 30 it rearwardly; and a series of lateral, intermediate partition plates within said shell, said arm passing through all of said plates to act as a support for said shell.

3. A blade construction for propellers comprising: a hub member; a blade arm extending radially outward from said hub member; a curved propeller shell positioned to receive a stream of air from the direction of rotation and 5 discharge it rearwardly; a series of lateral, intermediate partition plates within said shell, said arm passing through all of said plates to act as a support for said shell; and stream-lined shield members hanging loosely on said arms 10 between each pair of said partition plates, said shell being inclined with reference to said blade arm so as to gradually approach the latter as the distance from the axis is increased.

4. A blade construction for propellers comprising: a hub member; arms extending radially outward from said hub member; transversely curved propeller shells mounted on said arms, said shells having the largest cross-sectional area near the said hub member and tapering 20 gradually toward the outer end where the cross-section area is comparatively small.

5. A blade construction for propellers comprising: a hub member; scoop-shaped cups mounted 25 radially outward on said hub member, said cups being open in the direction of rotation and at their rearward faces so as to receive a stream of air, curve it, and expel it rearwardly, said cups being completely curvated so that any line on their inner or outer surfaces will be a curved 30 line.

WILLIAM H. KELLY.
